UNITED STATES PATENT OFFICE.

HERBERT R. MILLER, OF FORT WAYNE, INDIANA.

PAPER RECEPTACLE.

Application filed January 16, 1922. Serial No. 529,446.

To all whom it may concern:

Be it known that I, HERBERT R. MILLER, a citizen of the United States, residing at Fort Wayne, in the county of Allen and State of Indiana, have invented new and useful Improvements in Paper Receptacles, of which the following is a specification.

The invention relates to receptacles formed of paper and particularly to such receptacles adapted for the storage of various articles, such as wearing apparel, blankets, furs, and the like in and about the home, and the protection of the same from dust and dirt and moths.

The object of the invention is to provide a cheap receptacle which shall be collapsible for shipment and storage purposes and therefore occupy a minimum of space, and which shall be capable of easy setting up for use and have a maximum of strength, the receptacle when closed being adapted to fully protect its contents against the entrance of dust, moths, etc.

I accomplish the invention by providing a paper bag having a reinforced bottom, with a relatively heavy cover adapted to be closed thereon in novel manner, the side walls being reinforced by a collapsible reinforcement which is removable therefrom in order to collapse the receptacle.

I have illustrated an embodiment of the invention in the accompanying drawings, in which

Figure 1 is a plan view of the receptacle with the cover in upright position; Fig. 2 an end elevational view of the same; Fig. 3 a front elevational view of the receptacle in closed condition; Fig. 4 a plan view of the receptacle in collapsed condition; Fig. 5 a front elevational view of the same; Fig. 6 a side elevational view of the same; Fig. 7 a detail sectional view of the cover sealing pocket; Fig. 8 a plan view of one of the reinforcement members; Fig. 9 an elevational view of the same and Fig. 10 a perspective view of the receptacle in set up condition.

Referring to the drawings, the receptacle comprises a bag 1 of any desired shape and permanently closed at the bottom. The bag is preferably formed of paper of suitable weight and the bottom 2 is reinforced on its inner face by a sheet of paper board 3 of suitable weight. When collapsed the end walls 4 fold inwardly as shown in Fig. 6 and by the broken lines 4^a in Fig. 2, the back wall

21 folds about on the line 22, the reinforcements being first removed from the receptacle and later placed in a collapsed condition on the collapsed receptacle for storage 60 or shipping purposes.

To reinforce the vertical walls of the bag in "set up" condition I provide a reinforcement formed of corrugated paper board in two sections 5 and 5'. Each section is scored 65 transversely at 6 and 7 in order that the section may be inserted in the bag or collapsed with ease. The portion 8 abuts the front wall 20 or back wall 21 of the bag, the portion 9 abuts one of the end walls of the 70 bag and the short portion 10 abuts the inner face of the portion 8 of the other section as shown in Fig. 1. The side walls of the bag are therefore rigidly reinforced and the contents of the receptacle contact with the reinforced 75 bottom and the reinforcing sections 5 and 5'. Each section 5, 5' may be collapsed on the scorings 6 and 7 so that the portions 9 and 10 will flatten out on the portion 8 as shown in Fig. 6. 80

A cord 11 or other suitable reinforcement is inserted in the top of the bag, the material of the top being folded over the cord and suitably secured to the said top below the cord. A strip 12 having a similar cord 85 13 similarly secured in its upper edge is suitably secured to the walls of the receptacle adjacent their upper edges, the upper edge of the strip being below the upper edges of the walls of the receptacle. 90 The strip is placed preferably on the outside surfaces of the front and end walls only and forms a pocket 18 on the exterior and at the top of the receptacle to receive the flanges 14 of the cover 15. 95

The cover 15 is hinged in suitable manner to the rear wall of the receptacle and carries one or more finger grips 16 by which it may be elevated to open the receptacle.

The rear end of each side flange 14 of the 100 cover is notched or cut out at 17 to form a nose 19. When the cover is to be closed, the nose 19 on each flange 14 is first inserted in the rear end of the pocket, the remainder of the flange then readily passing into the 105 pocket as the cover is closed. The front flange is readily inserted in the front portion of the pocket. The forward end of each side flange 14 is rounded off at its lower corner and in like manner the opposite ends 110 of the front flange are rounded off so that when the cover is closed on the body portion

of the receptacle formed by the bag the flanges will accurately seat in the pocket and not interfere with each other at their adjacent ends

- 5 It will be noted that the pocket 18 is continuous on the exterior of the body of the receptacle from one end of its rear wall to the opposite end of that wall, and being thus continuous the corners of the receptacle are 10 fully protected against the entrance of foreign matter or moths. Since the cover is hinged to the rear wall of the body it is unnecessary that the pocket shall be formed on that wall, but if the cover should be made 15 separate then the pocket should be continued on the rear wall as well. I prefer the unitary construction of cover and body illustrated.

In practice I treat the reinforcing linings 20 3 and 5, 5' with suitable moth repelling material so that when the receptacle is closed it is substantially moth proof and forms a cheap chest for the storage of woollens, furs and other apparel and articles. The 25 strength of each chest is such that several of them may be stacked one upon another without danger of collapse and injury to the contents of any one of them.

What I claim is:

- 30 1. In an article of the class described a paper body having a reinforced bottom permanently closing the same, the side walls of the body being adapted to collapse upon the said bottom, means secured to the face of the side walls of the body and adjacent the upper edges thereof to form a pocket about said edges and a cover having depending side flanges adapted to be inserted into the said pocket.
- 40 2. In an article of the class described a paper body having a reinforced bottom permanently closing the same and having its side walls adapted to collapse upon the said bottom, removable reinforcing means 45 adapted to reinforce the side walls, means on

the exterior face of the side walls to form a pocket adjacent the upper edge or mouth of the body, said pocket being continuous, and a cover hinged to one of the side walls and having depending flanges at its edges 50 adapted to be inserted into the said pocket for closing the body.

3. In an article of the class described a paper bag permanently closed at its bottom and having its side walls adapted to collapse 55 upon the said bottom, removable means within the bag for reinforcing the side walls, a pocket formed on the exterior face of the side walls adjacent the upper edges thereof, a cover for the bag having marginal flanges depending therefrom and adapted to be inserted into the said pocket and means on some of the flanges for guiding the flanges into the pocket.

4. A paper receptacle comprising a body 60 portion permanently closed at its bottom and having its side walls adapted to collapse upon the said bottom, means to reinforce the upper edge or mouth of the body portion, a cover hinged to one wall of the body and 65 having depending marginal flanges, a reinforced strip secured to the outer face of the side walls adjacent the mouth of the body portion forming a continuous pocket from one end of the cover to the opposite end and 70 adapted to receive the flanges on the cover, the end of each flange adjacent the hinge having a member formed thereon adapted to guide the said flange into the pocket, and a two-section member removably supported 75 in the body portion for reinforcing the side walls thereof, each said section being adapted to collapse and having, when installed, a portion of the same overlapping the other section.

In witness whereof I have hereunto subscribed my name this 6th day of January, 1922.

HERBERT R. MILLER.
